(57) **CLAIM**

The ornamental design for spa shell seating, as shown and described.

DESCRIPTION

FIG. 1 is a perspective view of a new design for spa shell seating.

FIG. 2 is a front view of FIG. 1.

FIG. 3 is a back view of FIG. 1.

FIG. 4 is a left side view of FIG. 1.

FIG. 5 is a right view of FIG. 1.

FIG. 6 is a top view FIG. 1.

FIG. 7 is a bottom view of FIG. 1; and,

FIG. 8 is another perspective view of the design shown in FIG. 1.

The broken lines in the drawings illustrate environmental structure and portions of the spa shell seating that form no part of the claimed design. The dot-dash-dot broken lines define the bounds of the claimed design and form no part thereof.

1 Claim, 6 Drawing Sheets
